(57) **CLAIM**

The ornamental design for a child-resistant container assembly, as shown and described.

DESCRIPTION

FIG. 1 is a top perspective view of a child-resistant container assembly.

FIG. 2 is a top plan view of the child-resistant container assembly of FIG. 1.

FIG. 3 is a bottom plan view of the child-resistant container assembly of FIG. 1.

FIG. 4 is a first side view of the child-resistant container assembly of FIG. 1.

FIG. 5 is a second side view, which is opposite of the first side view of FIG. 4.

FIG. 6 is a first end view of the child-resistant container assembly of FIG. 1.

FIG. 7 is a second end view, which is opposite of the first end view of FIG. 6.

FIG. 8 is a top perspective view of the inner component depicted on the left side of the child-resistant container assembly of FIG. 1, shown separately to reveal aspects of the design that may not be apparent in other views; and, FIG. 9 is a bottom perspective view of the inner component of FIG. 8.

1 Claim, 5 Drawing Sheets
